UNITED STATES PATENT OFFICE.

WILLIAM A. ERICKSEN, OF BROOKLYN, NEW YORK.

FLASH-LAMP WITH EXTENSION.

1,282,655.

Specification of Letters Patent. Patented Oct. 22, 1918.

Application filed April 22, 1918. Serial No. 230,471.

To all whom it may concern:

Be it known that I, WILLIAM A. ERICKSEN, a subject of the King of Norway, and a resident of the city of New York, borough of Brooklyn, in the county of Kings and State of New York, have invented a new and Improved Flash-Lamp with Extension, of which the following is a full, clear, and exact description.

10 This invention relates to electric lamps of the type ordinarily called flash lamps or flash lights and of a form or construction suitable for carrying in one's hand or pocket or for use on or in connection with various tools, machinery, or the like, usually for temporary or emergency purposes as distinguished from standard light facilities such as regularly installed gas or electric lamps.

15 Among the objects of this particular invention is to provide a flash lamp having peculiar facilities for supporting the bulb directly thereon in connection with the flash lamp casing in a manner somewhat similar to an ordinary flash lamp, but having also a 20 flexible extension whereby the bulb is adapted for extended use or manipulation at some distance from the casing or battery while the latter may be supported in relatively fixed position.

25 Another object of the invention is to provide a flash lamp with an extension but having facilities for coiling the extension within the casing in a neat and compact position while the device is being used as an ordinary flash lamp or carried in one's pocket.

30 With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like 35 reference characters designate the same parts in the several views, and in which—

40 Figure 1 is a vertical sectional view showing my device complete and with the bulb and extension cord in normal housed position within the cap portion of the casing.

45 Fig. 2 is a horizontal sectional view on the line 2—2 of Fig. 1.

50 Fig. 3 is a plan view of the top of the main or body portion of the casing.

55 Fig. 4 is a side elevation of the lamp complete with the bulb extended.

Fig. 5 is a perspective view indicating a preferred type of bracket for holding the casing as for example upon the arm of a sewing machine.

60 Fig. 6 is a detail perspective view of a clip for holding the lamp bulb in extended position with respect to the casing as for instance upon one's finger for shaving or like purposes, upon a pen or pencil for writing purposes, for attachment to the presser bar of a sewing machine for throwing the light upon the work at the sewing machine, or for any other various purposes; and

65 Fig. 7 is a sectional detail of the bottom 70 of the casing and battery indicating the nature of the bottom closure of the casing.

70 Referring now more particularly to the drawings, I show a casing body 10 of any suitable construction and designed to inclose 75 a battery 11 having fixed terminals 12 and 13 at its upper end. The casing may be provided with a bottom closure 14 hinged at 15 for the purpose of inserting or removing the battery. Any suitable finger piece or switch 80 16 may be provided to complete the circuit when desired as usual.

75 The top 17 of the casing body made preferably of sheet metal or the like is slotted or stamped out as shown in Figs. 1, 2 and 3 to 85 provide a pair of upwardly directed prongs 18 spaced from each other on opposite sides of the center of the top for the accommodation of the lamp bulb socket 19 which is in the nature of a hood or reflector for intensifying the light from the bulb 20 fixed thereina in any well known manner. Circuit wires 21 and 22 lead from the lamp socket and lamp to the terminals 12 and 13 through what may be termed a flexible cord 23. It 90 will be understood that the contacts or binding posts 12' and 13' have direct contact with the terminals 12 and 13 respectively of the battery while the battery is locked in place within the casing. The cord at any 100 convenient point where the two wires 21 and 22 come together may be anchored or guided through a staple or holder 24 thereby relieving the points of connection 12' and 13' from danger incident to the manipulation of the 105 lamp socket separate from the casing.

110 The socket 19 is provided on opposite sides with loops 25 which receive the upper or free ends of the prongs 18 and whereby the socket is held in upright position with the lamp directed upward so as to glow through the lens 26 held in any suitable manner in

the removable top or cap 27 of the casing. The cord 23 is adapted to be coiled upon the casing top 17 in such a position as to permit the cap 27 to close readily. For this purpose 5 I provide two other prongs or standards 28 similar to the prongs 18 and located preferably at equal distances from the center on opposite sides of the prongs 18, but preferably of less height than the socket prongs 10. The operator in order to nest the lamp within the casing top or cap simply coils the cord around all of the prongs bringing the socket finally down into its central position over the prongs 18. The standards 28 will 15 act primarily as a means to hold the cord in place so as not to interfere with the closing of the cap, while the lamp will be held in position with sufficient security to operate as an ordinary flash lamp, as well illustrated 20 in Figs. 1 and 2.

In order to use the extension the operator removes the cap 27, lifts the lamp socket 19 from the prongs 18 and then brings the cord or as much of it as is needed from the 25 standards 28 and then replaces the cap 27 the extended portion of the cord passing through a notch 29 formed in the edge of the cap at any desired point.

Fig. 5 indicates a simple and reliable form 30 of bracket comprising an upright 30, a foot piece 31, a hook 32, and side arms 33. The hook 32 is adapted to embrace or extend over any convenient support as for example the head or arm of a sewing machine so as 35 to support the casing 10 upon the foot 31 and between the arms 33 in convenient position so that the socket 19 may be fastened by means of a temporary clamp such as indicated at 34 to the presser bar of the sewing 40 machine in position to throw the light from the bulb 20 down upon the work at the sewing machine. While the bulbs usually employed in these flash lamps are relatively small, requiring a small amount of energy, yet it is 45 well known that the light therefrom when sufficiently intensified by reflectors and lenses is sufficient for satisfactory practice when confined to small areas.

The clip 34 may assume various specific 50 designs or forms in practice but as indicated includes a ring formation 35 whereby it may be worn upon one's finger for writing, shaving, reading, or other purposes. It also includes a pair of jaws 36 and 37 adapted to embrace a small object such as the presser bar of a sewing machine or the like and to one of the jaws is secured a prong

38 upon which one of the ears or loops 25 may be slipped. The prong 38 may be carried by a disk like base 39 adjustable around its center so that the prong 38 may occupy any desired position with respect to the supporting means for the clip as a whole. 60

It will thus be seen that I provide a neat, convenient and reliable convertible flash 65 lamp of a type that may be used as an ordinary flash lamp and also as an extension lamp, special provision being made for the accommodation of the battery or casing portion of the lamp as well as for the control 70 of the lamp socket or bulb portions.

The lamp socket 19 is provided preferably on one side only with a hood 19' which constitutes sufficient extension to thoroughly 75 protect the eyes of the operator from any glare that may emerge from one side of the bulb 20. As shown in Fig. 1, however, ample room is provided within the lens 26 to accommodate the hood 19' as well as the socket. This hood furthermore may be provided with or constitute a reflector to give 80 added intensity to the light that is thrown outward or downward in the desired direction.

I claim:

1. In a flash lamp, a casing having a top provided with upwardly projecting members, a battery within the casing, a lamp socket, a bulb held in the socket, flexible cord connections between the lamp and the 90 battery, certain of said projecting members serving to receive the cord connections, means carried by the lamp socket and co-operating with the remainder of the projecting members to hold the lamp removably in position upon the casing top, and a cap 95 co-operating with the casing to house the lamp and connection wholly within the casing and having a lens registering with the bulb when held as thus specified. 100

2. In a flash lamp, a casing having a top of sheet material formed to provide upwardly projecting members, a battery within the casing, a lamp socket, a lamp bulb held in the socket, electrical connections between the lamp and the battery through said casing top, means carried by the lamp socket and co-operating with certain of said members to hold the lamp removably in central position upon the casing top, and a cap 110 co-operating with the casing to house the lamp and electrical connections wholly within the casing.

WILLIAM A. ERICKSEN.
